(57) **CLAIM**

The ornamental design for a fitting, as shown and described.

DESCRIPTION

FIG. 1 is a left perspective view of a first embodiment of a fitting;

FIG. 2 is a right perspective view of the fitting shown in FIG. 1;

FIG. 3 is a bottom perspective view of the fitting shown in FIG. 1;

FIG. 4 is a bottom left perspective view of the fitting shown in FIG. 1;

FIG. 5 is a rear perspective view of the fitting shown in FIG. 1;

FIG. 6 is a front perspective view of the fitting shown in FIG. 1;

FIG. 7 is a right front perspective view of the fitting shown in FIG. 1;

FIG. 8 is a right rear perspective view of the fitting shown in FIG. 1;

FIG. 9 is a left perspective view of the fitting shown in FIG. 1;

FIG. 10 is a left rear perspective view of the fitting shown in FIG. 1;

FIG. 11 is another front perspective view of the fitting shown in FIG. 1;

FIG. 12 is another left perspective view of the fitting shown in FIG. 1;

FIG. 13 is a top right perspective view of the fitting shown in FIG. 1;

FIG. 14 is another right perspective view of the fitting shown in FIG. 1;

(Continued)

FIG. 15 is a left perspective view of a second embodiment of a fitting;
 FIG. 16 is a right perspective view of the fitting shown in FIG. 15;
 FIG. 17 is a bottom perspective view of the fitting shown in FIG. 15;
 FIG. 18 is a bottom left perspective view of the fitting shown in FIG. 15;
 FIG. 19 is a rear perspective view of the fitting shown in FIG. 15;
 FIG. 20 is a front perspective view of the fitting shown in FIG. 15;
 FIG. 21 is a right front perspective view of the fitting shown in FIG. 15;
 FIG. 22 is a right rear perspective view of the fitting shown in FIG. 15;
 FIG. 23 is a left perspective view of the fitting shown in FIG. 15;
 FIG. 24 is a left rear perspective view of the fitting shown in FIG. 15;
 FIG. 25 is another front perspective view of the fitting shown in FIG. 15;
 FIG. 26 is another left perspective view of the fitting shown in FIG. 15;
 FIG. 27 is a top right perspective view of the fitting shown in FIG. 15; and,
 FIG. 28 is another right perspective view of the fitting shown in FIG. 15.
 The broken lines depict portions of the fitting that form no part of the claimed design. Dustopper is a registered trademark, registration number 5576639, of registrant Thomas E. Huntley, DBA Faster Better Easier, LLC, a LIMITED LIABILITY COMPANY OF MICHIGAN, and is illustrated in broken lines and forms no part of the claimed design.
